US0D1113067S

(12) **United States Design Patent** (10) **Patent No.:** **US D1,113,067 S**
(45) **Date of Patent:** **** Feb. 10, 2026**

(54) **SAFE**

(71) Applicant: **SA Consumer Products, Inc.**, Rolling Meadows, IL (US)

(72) Inventors: **Jeremy O'Halloran**, Brentwood, PA (US); **Edward E. Eckman**, Sewickley, PA (US); **Ben Lavallee**, McDonald, PA (US); **Richard Glogovsky**, Libertyville, IL (US); **Jesus Carballido**, Chicago, IL (US)

(73) Assignee: **SA Consumer Products, Inc.**, Rolling Meadows, IL (US)

(**) Term: **15 Years**

(21) Appl. No.: **29/957,960**

(22) Filed: **Aug. 16, 2024**

(51) **LOC (15) Cl.** **99-00**

(52) **U.S. Cl.** **USPC** **D99/28**

(57) **CLAIM**

The ornamental design for a safe, as shown and described.

DESCRIPTION

FIG. 1 is a front perspective view of a safe showing our new design;
FIG. 2 is another front perspective view of FIG. 1, with the door in an open configuration;

FIG. 3 is a front view of FIG. 2;

FIG. 4 is a left side view of FIG. 1;

FIG. 5 is a right side view of FIG. 1;

FIG. 6 is a back view of FIG. 1;

FIG. 7 is a bottom view of FIG. 1; and,

FIG. 8 is a top view of FIG. 1.

The broken lines in the drawings depict portions of the safe that form no part of the claimed design.

1 Claim, 7 Drawing Sheets
